UNITED STATES PATENT OFFICE.

CHARLES A. SHOEMAKER, OF CHICAGO, ILLINOIS.

TANK-CAR.

1,026,710.

Specification of Letters Patent.

Patented May 21, 1912.

Application filed May 26, 1911. Serial No. 629,676.

To all whom it may concern:

Be it known that I, CHARLES A. SHOEMAKER, a citizen of the United States, residing at Chicago, in the county of Cook 5 and State of Illinois, have invented a certain new and useful Improvement in Tank-Cars, of which the following is a full, clear, concise, and exact description, reference being had to the accompanying drawings, 10 forming a part of this specification.

My invention relates to tank car structures and has for its object the provision of improved means for opposing endwise movements of tanks with respect to the under frames supporting the same. 15

In practising my invention gravity is employed for counteracting end thrusting movements of tanks, the tanks being caused to rise when the under frames supporting 20 the same are subjected to sufficient blows or pulls to cause the tanks to move longitudinally with respect to the under frames. The mechanism which I prefer to employ for permitting the tanks to rise also takes 25 part in automatically restoring the tanks to normal positions with respect to their under frames after the tanks have risen.

In the preferred embodiment of my invention I provide friction contacting surfaces, which slope with respect to the horizontal, upon either the tank or the under frame and preferably upon both the tank and the under frame, these surfaces sloping lengthwise of the tank so that the tank is 30 permitted normally to settle to a predetermined position with respect to the under frame and is forced to climb when the under frame is subjected to blows or pulls of sufficient force to effect relative movement of 35 the tank and under frame. In a structure thus devised the rivets that are employed for assembling the tank and under frame are relieved of effective shearing stresses, this being particularly the case when the 40 contacting surfaces of the under frame and tank are in frictional engagement, the friction then coöoperating with gravity in opposing endwise movements of the tank with respect to its under frame.

50 I will explain my invention more fully by reference to the accompanying drawings in which—

Figure 1 is a side elevation, partially in section, of a tank car structure made in 55 accordance with the preferred embodiment of my invention, a part of the structure be-

ing broken away owing to the lack of space for its illustration; Fig. 2 is a cross sectional view of a part of the structure as it appears in Fig. 1; Fig. 3 is a detail view of a part of the structure shown in Fig. 1 but on a larger scale; Fig. 4 is a sectional view on line 4-4 of Fig. 3; Fig. 5 is a bottom view of the tank element of the car structure where such element is provided with contacting surfaces for causing the tank element to rise and permitting it to descend; and Fig. 6 is a plan view of the contacting faces provided upon the under frame of the car structure for coöperation with the contacting surfaces shown in Fig. 5.

Like parts are indicated by similar characters of reference throughout the different figures.

The tank car structure includes two main 75 elements, one, the tank element and parts attached thereto, and the other, the under frame element and the parts attached thereto and the trucks or wheels that constitute this under frame a vehicle for supporting the tank. 80 A third element in the organization resides in some means for normally holding the tank down and which will permit the tank to rise under the circumstances which have been mentioned. The under frame element shown includes two longitudinally extending center sills 1 carrying as many saddles 2 as may be desired for the purpose of carrying the tank 3 and permitting said tank to move longitudinally of the center 90 sills. I have indicated one such saddle 2 at the right hand end of such structure as it appears in Fig. 1, it being understood that a similar saddle is symmetrically disposed at the other end of the structure, its illustration being omitted because of the lack of space. The third element of the structure is preferably in the form of tank bands 4 that engage the tank 3 and are anchored at their ends to tank band lugs 5 that are secured to the bottom flanges of the center sills 1. The free ends of the tank bands are desirably threaded, as illustrated very clearly in Fig. 4, for the reception of nuts 6. Heavy springs 7 surround the extremities of the tank bands and are interposed between the lugs 5 and nuts 6. These springs are sufficiently strong normally firmly to hold the tank down upon its saddles 2, but are adapted to yield when the center sills receive sufficiently strong 100 blows or pulls to cause the tank to move 105 110 115 120 125 130 135

lengthwise of the under frame to permit the tank to rise in accordance with the general object of my invention.

The tank element of the car structure is, in accordance with the preferred embodiment of my invention, provided with at least two friction contacting surfaces that slope longitudinally of the entire structure in directions that converge from opposite sides of a vertical line located between such surfaces, these contacting surfaces being desirably afforded by the employment of a cast block 8 desirably in the form of a flattened V, this block 8 being preferably cast integrally with a plate 9 that is riveted at its edges to the bottom of the tank 3. The block portion 8 of the casting 8, 9 is desirably so located and is of a size to permit of its entry into the space between the center sills and in effect constitutes a downwardly extending projection upon the bottom of the tank. The under frame element of the tank car is provided with a V-shaped seat 10 formed in the top part of a casting 11 riveted to the center sills, this casting desirably having vertical wings 12 engaging the inner vertical faces of the center sills 1 and horizontal wings 13 that engage the top flanges of the center sills. Fastening rivets are passed through these wings 12 and 13 into the contiguous portions of the center sills. The V-shaped block 8 has its bottom surfaces sloping in opposite directions toward a vertical line intervening between said surfaces and longitudinally of the tank and the seat surfaces 10, which frictionally engage the bottom of the block 8, desirably slope similarly and at similar angles. Referring to Figs. 1 and 3, it will be seen that the seat faces 10 of the casting 11 are slightly longer, longitudinally of the tank, than the engaging surfaces of the block 8 and that clearance exists between the opposite ends of the block 8 and the contiguous portions of the block 11, 45 whereby the block 8 is permitted to move obliquely upon the block 11 in either direction toward the ends of the car structure, such movement of the block 8 upon the block 11 occurring when the under frame structure receives blows of sufficient force to effect longitudinal movement of the tank upon its supporting under frame. The longitudinal movement of the tank is permitted owing to the fact that the tank may slide 55 upon its saddles 2. The movement of the block 8 is permitted owing to the yielding connections 7 between the tank bands and the under frame, the connections or springs 7 permitting the ends of the tank bands to 60 rise with the tank as the tank itself rises owing to the upward movement of the block 8 upon the block 11. When the force that has caused the upward movement of the tank upon its under frame has been spent, 65 the block 8 will, owing to the action of

gravity, settle to its central position upon the block 11 whereby the normal position of the tank with respect to the under frame is restored. The restoration of the block 8 to its central position is aided by the action of the springs 7 that coöperate with gravity to effect this result.

If desired, stops 14 may be provided upon the under frames and may face the outer transverse edges of the block 8 for the purpose of engaging these transverse edges and limiting the extent to which the tank may rise and move along the under frame. These stops 14 may be cast integrally with the block 11 and are located sufficiently far from the block 8 so as not to be engaged by said block when the under frame is subjected to thrusting or pulling strains within a predetermined range. When this range is exceeded the block 8 engages one or the other of the stops 14 so as to limit the extent of the longitudinal movement of the tank upon the under frame.

I have shown but one block 8 and one block 11 which are illustrated as being in the center of the tank car structure. These two blocks 8 and 11 are sufficient when the tank is not of great length or very large capacity. The number of the parts 8 and 11 may be multiplied and be positioned as may be desired to suit requirements.

While I have herein shown and particularly described the preferred embodiment of my invention, I do not wish to be limited to the precise construction shown for carrying the invention into effect as obviously many changes may be made without departing from the spirit of the invention.

Having thus described my invention I claim as new and desire to secure by Letters Patent the following:

1. A tank car structure including a tank which may rise from its support; an under frame for supporting the tank and permitting movement of the tank longitudinally thereon the tank and underframe structures having friction faces in frictional engagement; and means for forcing the tank to rise against the action of friction when the tank is moved longitudinally of the under frame.

2. A tank car structure including tank and under frame elements between which relative movement longitudinally of the car structure may occur and which tank may rise from the underframe, one of said elements of the car structure having a friction surface sloping with respect to the horizontal and longitudinally of the car structure and which surface is frictionally engaged by the other of said elements of the car structure whereby the tank is caused to rise when it is moved longitudinally of the under frame.

3. A tank car structure including tank

- and under frame elements between which relative movement longitudinally of the car structure may occur and which tank may rise from the under frame, the car structure 5 having sloping surfaces which are frictionally engaged to support the tank in different positions, one of said sloping surfaces being positioned to force the tank to rise when it is moved in one direction from normal position longitudinally of the under frame and the other of said sloping surfaces being positioned to force the tank to rise when it is moved in the other direction longitudinally of the under frame.
- 10 4. A tank car structure including tank and under frame elements between which relative movement longitudinally of the car structure may occur and which tank may rise from the under frame, each of said elements of the car structure having oppositely sloping friction surfaces which are frictionally engaged by the sloping friction surfaces upon the other element of the car structure, one set of engaging sloping surfaces 20 being positioned to force the tank to rise when it is moved in one direction from normal position longitudinally of the under frame and the other set of engaging sloping surfaces being positioned to force the tank to rise when it is moved in the other direction longitudinally of the under frame.
- 25 5. A tank car structure including a tank which may rise from its support; an under frame for supporting the tank and permitting movement of the tank longitudinally thereon, the tank and under frame structures having friction faces in frictional engagement; means for forcing the tank to rise against the action of friction when the tank 30 is moved longitudinally of the under frame; and means for yieldingly holding the tank down upon the under frame.
- 35 6. A tank car structure including tank and under frame elements between which relative movement longitudinally of the car structure may occur and which tank may rise from the under frame, one of said elements of the car structure having a friction surface sloping with respect to the horizontal and longitudinally of the car structure 40 and which surface is frictionally engaged by the other of said elements of the car structure whereby the tank is caused to rise when it is moved longitudinally of the under frame; and means for yieldingly holding the tank down upon the under frame.
- 45 7. A tank car structure including tank and under frame elements between which relative movement longitudinally of the car structure may occur and which tank may rise from the under frame, one of said elements of the car structure having a friction surface sloping with respect to the horizontal and longitudinally of the car structure 45 and which surface is frictionally engaged by the other of said elements of the car structure whereby the tank is caused to rise when it is moved longitudinally of the under frame; and means for yieldingly holding the tank down upon the under frame.
- 50 8. A tank car structure including tank and under frame elements between which relative movement longitudinally of the car structure may occur and which tank may rise from the under frame, the car structure 50 having sloping surfaces which are frictionally engaged to support the tank in different positions, one of said sloping surfaces being positioned to force the tank to rise when it is moved in one direction longitudinally of the under frame and the other of said sloping surfaces being positioned to force the tank to rise when it is moved in the other direction longitudinally of the under frame; and means for yieldingly holding the tank down upon the under frame.
- 55 9. A tank car structure including tank and under frame elements between which relative movement longitudinally of the car structure may occur and which tank may rise from the under frame, each of said elements of the car structure having oppositely sloping surfaces which are frictionally engaged by the sloping surfaces upon the other element of the car structure, one set of engaging sloping surfaces being positioned to force the tank to rise when it is moved in one direction longitudinally of the under frame and the other set of engaging sloping surfaces being positioned to force the tank to rise when it is moved in the other direction from normal position longitudinally of the under frame; and means for yieldingly holding the tank down upon the under frame.

In witness whereof, I hereunto subscribe my name this 24th day of May A. D., 1911.

CHARLES A. SHOEMAKER.
